DECANTER

Hyman C. Berkowitz, Wendell, Idaho, assignor to Berke Brothers Distilleries Inc., Boston, Mass.,
a corporation of Delaware

Application March 30, 1953, Serial No. 24,244

Term of patent 14 years

(Cl. D58—8)

To all whom it may concern:

Be it known that I, Hyman C. Berkowitz, a citizen of the United States, residing at Wendell, in the county of Gooding and State of Idaho, have invented a new, original, and ornamental Design for a Decanter, of which the following is a specification, reference being had to the accompanying drawings, forming a part thereof.

In the drawings:

Fig. 1 is a front view of a decanter showing my new design.

Fig. 2 is a side view looking to the left of Fig. 1.

Fig. 3 is a plan view of the decanter.

The rear view of the decanter is the same as the front view as shown in Fig. 1, and the right side of the decanter is the same as the left side as shown in Fig. 2.

I claim:

The ornamental design for a decanter, substantially as shown and described.

HYMAN C. BERKOWITZ.
